D12-20. OR D 13,409 EX

NO. 13,409

Nov 14, 1882

UNITED STATES PATENT OFFICE.

JOHN L. POPE, OF CLEVELAND, OHIO.

DESIGN FOR A WEAR-IRON.

SPECIFICATION forming part of Design No. 13,409, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Wear-Irons, of which the following is a specification, reference being had to the accompanying engraving, forming part thereof.

My invention relates to a design for wear-irons for use on carriages and other vehicles; and it consists in the general shape of the article, and also in certain features of adornment of the same, as will be hereinafter more particularly described in this specification, and pointed out in the claims thereof.

In the accompanying engraving, $a a' a^2$ represent three lengthened lug-like portions, each of which is provided with a hole for the passage therethrough of a screw, nail, or other device to secure the "iron" to the desired part of the vehicle, as customary. These ear-like portions $a a' a^2$ are reduced in width where they join the main part of the wear-iron, b , and have their outer extremities rounded or curved, as plainly seen. Along one edge of the main portion b runs a rounded bead or rib, c , which

is bent or turned at each end of the iron, and extends for a short distance along the elongated lugs $a a^2$, on the outer edges thereof. From this rounded bead c extends a branch bead, d , of similar shape, along the middle of the lug a' for a distance about equal to the extension of the bent portions c along the lugs $a a^2$, as plainly shown.

What I claim as my invention, and desire to secure by Design Letters Patent, is—

1. A wear-iron having three lug-like extensions, with reduced portions where they join the main part b , and with their outer extremities curved or rounded in contour, substantially as shown and described.

2. A wear-iron having the portion b ornamented with a rounded bead, c , and branch d , said ornamentation extending along the lugs for a short distance, substantially as shown and described.

In testimony whereof I have hereunto set my hand this 22d day of June, 1882.

JOHN L. POPE.

In presence of—

CHAS. W. MOSES,
C. M. COPP.
